LOOSE LEAF BINDER

Erik L. Krag, Chicago, Ill., assignor of one-tenth
to E. J. Andrews, Chicago, Ill.

Application July 10, 1930, Serial No. 467,098

4 Claims. (Cl. 129—9)

This invention relates to loose-leaf binders and particularly to binders of this nature in which it is often desired to shift the leaves from one set of prongs to another. One object of the invention is to provide simple and effective means for separating the prongs when it is desired to remove or change leaves. Another object is to provide for suitable locking means when the binder is closed to prevent shifting or separating of the prongs. Another object of the invention is to provide means for indicating to the operator the position of the prongs with reference to the normal position and with reference to each other. Other objects of the invention will be apparent from a consideration of the drawings and the accompanying description thereof.

Of the drawings, Fig. 1 is a plan view of the inner side of a binder back when the binder is open, with certain parts removed, which embodies some of the features of my invention; Fig. 2 is a similar view with other portions of the mechanism removed; Fig. 3 is an enlarged sectional view along the line 3—3 of Fig. 1; and Fig. 4 is an enlarged sectional view along the line 4—4 of Fig. 1.

Referring to Figs. 1 to 4, the binder mechanism which I have invented consists of means for moving the prongs both transversely and longitudinally of the binder back, so that the prongs may be separated so as to remove the leaves, and the prongs, if desired, then may be shifted longitudinally with reference to each other, so as to shift leaves from one set of prongs to another, thus changing the position of the leaves in the binder itself.

The mechanism comprises a plate 10 to which is fastened, in any suitable manner, the binder back 11, which supports the covers 12 in an ordinary manner. Slidably mounted on the plate 10 is a bar 13 which, when moved inwardly or outwardly, is arranged to move the prongs transversely of the frame. The prongs 35 are fixed to bars 29 which are mounted upon transversely movable bars 15. These bars are pivotally connected to links 16 by means of bars 9 to which the bars 15 are fixed. The other ends of the links are pivoted to levers 17, the levers being pivoted to the plate 10. Also pivotally connecting the bar 13 with the levers 17 are links 18. As is indicated, the arrangement of these elements is such that, when the bar 13 is pulled outwardly, the bars 15 will be forced inwardly by the levers 17. Or when the bar 13 is forced inwardly, the bars 15 will be forced outwardly, thus

separating the prongs from each other, as is indicated in Fig. 3.

In order to manipulate the bar 13, a handle 20 is fixed thereto. In order to lock the bar in the closed position of the binder any suitable means may be used. I prefer to use a latch 21 pivoted, by means of a flange 22, to the bar 13. When the bar 13 is pulled outwardly, the end 23 of the latch passes against a shoulder 24 fixed to the plate 10. A spring 25 at all times tends to hold the end 23 in its elevated position. When it is desired to separate the prongs, the end 26 of the latch is forced upwardly so as to release the end 23.

The prongs 35 are fixed to bars 29 which are slidably mounted for longitudinal movement on the bars 15. In order to prevent movement of the prong bars 29 longitudinally of the frame when the prongs are closed, any suitable means may be provided. I prefer for the purpose a finger 30 which is mounted on a plate 38 by means of a spring 36 and a lug 37. The finger is adapted to pass into a notch 31 in a plate 33. The plate 38 is fixed relative to the base plate 10. The plate 33 passes over the prongs 35, and rests on the bar 15. When the prongs are closed, the back of the finger 30 will rest against a stop 32 fixed to the plate 38, and this will prevent further backward movement of the finger and, hence, will hold the plate 33 from longitudinal movement. However, when the prongs are separated, as indicated in Fig. 3, the finger 30 is at liberty to move away from the plate 33 and, hence, the plate 33 may be shifted longitudinally of the bar 15 in an ordinary manner with the prong bar 29.

The prong bars 29 may be shifted in the bar 15 as far as may be desired. A notch 34 is provided in the plate 33 corresponding to the position of each of the prongs 35. As a consequence, when the prongs are shifted longitudinally, the finger 30 will stop the movement at such a position that the prongs will register with the other set of prongs. The notches 31 and 34 are numbered consecutively corresponding to the numbers of the prongs from the end, so that the position of the prongs will be indicated.

A similar finger is provided for controlling the movement of the corresponding plate 33, but it is placed at the opposite end of the binder back, as the prong bars are preferably shifted longitudinally in opposite directions. Handles 8 are used to operate the prong bars 29.

I claim as my invention:

1. In a loose-leaf binder, a base plate, a pair of

55

- prong plates mounted on said base plate, paper holding prongs fixed to each of said prong plates, one of said prong plates being movably mounted, means for moving said movable plate transversely of said base plate, said means comprising a bar mounted for longitudinal movement with reference to said movable plate, levers pivoted with reference to said base plate, a link pivotally connecting one arm of each lever with said bar, and a link pivoted to each of the other arms of said levers and being pivotally associated with said movable prong plate.
5. In a loose leaf binder, a base plate, a pair of prong bars, means for mounting said prong bars on said plate for movement transversely of said plate and also for movement longitudinally of said plate a distance equal to the length thereof, means for operating said bars transversely, means for preventing longitudinal movement of one of said bars when said binder is closed, said latter means comprising a stop fixed with reference to said base plate and a finger adapted to coact with said stop and with said prong bar to prevent movement of said prong bar.
10. In a loose leaf binder, a base plate, a pair of prong bars, means for mounting said prong bars on said plate for movement transversely of said plate and also for movement longitudinally of said plate a distance equal to the length thereof, means for operating said bars transversely, means for preventing longitudinal movement of one of said bars when said binder is closed, said latter means comprising a stop fixed with reference to said base plate and a finger adapted to coact with said stop and with said prong bar to prevent movement of said prong bar.
15. In a loose leaf binder, a base plate, a pair of prong bars, means for mounting said prong bars on said plate for movement transversely of said plate and also for movement longitudinally of said plate a distance equal to the entire length thereof, means for operating said bars transversely, means for preventing longitudinal movement of one of said bars when said binder is closed, said latter means comprising a stop fixed with reference to said base plate and a finger adapted to coact with said stop and with said prong bar to prevent movement of said prong bar.
20. In a loose leaf binder, a base plate, a pair of prong bars, means for mounting said prong bars on said plate for movement transversely of said plate and also for movement longitudinally of said plate a distance equal to the entire length thereof, means for operating said bars transversely, means for preventing longitudinal movement of one of said bars when said binder is closed, said latter means comprising a stop fixed with reference to said base plate and a finger adapted to coact with said stop and with said prong bar to prevent movement of said prong bar.
25. In a loose leaf binder, a base plate, a pair of prong bars, means for mounting said prong bars on said plate for movement transversely of said plate and also for movement longitudinally of said plate a distance equal to the entire length thereof, means for operating said bars transversely, means for preventing longitudinal movement of one of said bars when said binder is closed, said latter means comprising a stop fixed with reference to said base plate and a finger adapted to coact with said stop and with said prong bar to prevent movement of said prong bar.

3. In a loose leaf binder, a base plate, a pair of prong bars, means for mounting said prong bars on said plate for movement transversely of said plate and also for movement longitudinally of said plate a distance equal to the length thereof, means for operating said bars transversely, means for preventing longitudinal movement of one of said prong bars when said binder is closed, said means comprising a stop fixed with reference to said plate and a finger adapted to coact with said prong bar and stop to prevent movement of said prong bar when said binder is closed, and resilient means for moving said finger with said prong bar as the bar is moved transversely.

4. In a loose leaf binder, a base plate, a pair of prong bars, means for mounting said prong bars on said plate for movement transversely of said plate and also for movement longitudinally of said plate a distance equal to the entire length thereof, and means for operating said bars transversely, said operating means comprising a bar slidably mounted with reference to said plate, levers pivoted to said plate, and links pivotally connecting said operating bar and said prong bar mounting means with said levers.
